LIQUID FUEL HEATER

Daniel Murray Foley, New York, N.Y., assignor to West Coast Steel Products Co., Riverside, Calif., a corporation of California

Filed Nov. 7, 1955, Ser. No. 545,407

3 Claims. (Cl. 158—91)

This invention relates to improvements in liquid fuel heaters of the type commonly used for orchard heating purposes, and as space heaters in manufacturing plants and the like.

The conventional liquid fuel heater of this type consists of a receptacle adapted to contain an adequate supply of liquid fuel, such as fuel oil. On the top of this receptacle there is a cover in which there is an opening through which the receptacle can be refilled and through which a torch may be inserted for the purpose of igniting the fuel oil in starting the heater. This opening is normally covered by an adjustable air regulator which permits air to enter the receptacle and to mix with vapors generated from the surface of the fuel oil. The usual cover has an upstanding collar which has now been more or less standardized to have a 6" diameter. On this collar there is positioned an upstanding stack. The stack frequently is made up of two or even more sections of sheet metal which telescopically fit together. The lower of these sections usually has air inlet openings formed in the walls thereof through which additional air may enter the stack to complete combustion. This lower section frequently has the air inlet openings in the form of downwardly directed louvers and consequently, it is frequently referred to as the louvered section of the stack. It constitutes the combustion chamber of the heater inasmuch as most of the intense burning of the fuel takes place therein. This is highly desirable in that the walls of the louvered section become quite hot and tend to radiate the heat laterally, it being desirable that a direct ascent of the hot gases and products of combustion be minimized.

It has heretofore been recognized in heaters of this character that it is highly desirable to return to the covered fuel receptacle a portion of the heated products of combustion and/or some of the air that is admitted to the stack through the louver openings. The advantages of returning or re-circulating some of the products of combustion and/or air admitted to the stack have been recognized in United States Letters Patent No. 2,284,157, issued May 26, 1942, to Arthur Stephen Leonard. When a portion of the products of combustion and/or air admitted to the stack are returned to the fuel receptacle, a more complete combustion seems to result in that heater does not produce a noticeable amount of objectionable smoke and does not tend to "soot up."

The constructions disclosed in the Leonard patent, above referred to, contemplate the use of auxiliary stacks that are disposed externally of the main stack and which have downwardly directed entrances that are disposed in the main stack. A portion of the gases rising in the main stack, whether they be air or products of combustion, or a mixture of both, encounter the downwardly directed entrance to the auxiliary stack and on passing therethrough are returned by the auxiliary stack to the fuel receptacle.

An objection to that form of construction which is disclosed in the Leonard patent is that the construction is

2

relatively expensive to manufacture. Also, the presence of the auxiliary stack or stacks at the sides of the main stack is such as to frequently interfere with the positioning of the heater beneath a tree which is to be heated and kept from freezing during cold weather.

A primary object of the present invention is to provide an improved liquid fuel heater wherein a portion of the products of combustion and/or air are returned to the liquid fuel receptacle so as to gain the advantages of more complete combustion elimination of smoke and elimination of soot deposits. However, instead of adding an auxiliary stack to the exterior of the main stack I have found that if a tube is positioned in the main stack which has proper dimensions or proportions with respect to the main stack, the desirable return or re-circulation of a portion of the gases in the stack will be self-induced through the tube. Consequently, it is possible for me to gain all of the advantages of more complete combustion and at the same time reduce expense of manufacture and the objection of having an auxiliary stack at the side of the main stack which interferes with the positioning of the heater beneath a tree.

With the foregoing and other objects in view, which will be made manifest in the following detailed description and specifically pointed out in the appended claims, reference is had to the accompanying drawings for an illustrative embodiment of the invention, wherein:

Figure 1 is a top plan view of a heater embodying the present invention; and

Fig. 2 is a sectional view taken substantially upon the line 2—2 upon Fig. 1.

Referring to the accompanying drawings wherein similar reference characters designate similar parts throughout, the improved heater employs for purposes of convenience, expense, and simplicity of manufacture, a fuel receptacle 10 that may be conventional. This fuel receptacle is designed to receive and hold an adequate supply of liquid fuel, such as fuel oil 11. It is equipped with a cover 12 and in conformity with conventional practice this cover has an upstanding, centrally located, collar 13. The diameter of such collar has been more or less standardized by manufacturers of heaters of this type to have a 6" diameter. In the cover there is an opening 14 through which air may be admitted to the receptacle 10. The size of this opening can be adjusted or varied by a rotatable damper 15. The extent to which the opening is opened and the extent to which air is admitted to the fuel receptacle 10 governs to a large extent the rate of burning and the magnitude of the flame.

On the collar 13 there is positioned an upstanding stack and this stack is usually formed of two sections, the lower section being indicated at 16 and the upper section at 17. These two sections telescopically fit together and the lower section 16 forms the combustion chamber of the heater and is commonly referred to as the louvered section in that downwardly directed louvers 18 are formed in its walls. These louvers are formed by horizontally slitting the sheet metal from which the lower section 16 is formed and depressing inwardly the metal below the slit as indicated at 19. That portion of the metal which is immediately above the slit is pressed outwardly as indicated at 19' so that there are air openings formed in the walls of the louvered section for the ingress of air. As indicated on Fig. 1, I prefer to have ten vertical rows of louvers in a louvered section whose diameter at the collar 13 is approximately 6" and whose diameter at the top is approximately 8". These louvers are arranged in circumferential rows, the lowermost row being located approximately 3 $\frac{1}{16}$ " above the bottom of the louvered section. The uppermost row is preferably located 12 $\frac{1}{2}$ " above the bottom of the louvered section.

The upper portion 17 of the stack is generally imperforate and is cylindrical and its height seems to have no important bearing upon the present invention.

Within the louvered section there is disposed a central tube 20 preferably formed of seamless steel tubing having a wall thickness of $\frac{1}{8}$ ". Adjacent the top of this section of tubing steel straps 21 are welded to opposite sides thereof. Near the bottom of the tubing 20 a similar pair of straps 22 are welded to opposite sides thereof. These straps provide outwardly extending arms of upper and lower spiders, the lengths of which are such that they will engage the interior of the louvered section between the louvers and support the tubing therein with the top of the tubing 20 disposed at an elevation that is preferably even with the first row of louvers beneath the top row of louvers. At all events the top of the tubing 20 is disposed below the top row of louvers. The bottom of the tubing 20 extends down into the receptacle 10 a short distance. That is, it extends below the collar 13 on the cover and below the bottom edge of the louvered section.

I am aware that liquid fuel heaters of this general character have heretofore been provided wherein an open-ended tube is supported within the lower portion of the stack. However, in order to develop or self-induce a downward flow of air and/or products of combustion through the tube 20 in order to gain the advantages of re-circulation, the relative proportions of the tubing with relation to the louvered section are somewhat critical. In the preferred embodiment of my invention the length of the tubing 20 is 12" and has an outside diameter of 2" with a $\frac{1}{8}$ " wall thickness. It extends below the bottom of the collar 13 a distance of $1\frac{1}{2}$ ". In effect, therefore, the diameter of the tubing 20 is approximately one-third of the diameter of the collar 13 and the bottom of the louvered section. Also, the distance that the bottom of the tubing extends below the bottom of the collar 13 is approximately three-fourths of the diameter of the tubing. The length of the tubing may be regarded as being roughly six times its diameter with the tubing extending downwardly beneath the collar on the cover slightly less than a diameter.

When the tubing and louvered section have these relative proportions and the position of the tubing in the louvered section is as above described, it will be found that a relatively strong down-draft is self-induced in the tubing returning to the fuel receptacle 10 products of combustion and/or air that is admitted through the uppermost louver openings. This down-draft is readily observable if the upper section 17 of the stack is made of transparent material. Also, if a lighted wick is lowered through the upper section 17 to a location immediately above the top of the tubing 20 the flame from the wick will be observed to be drawn downwardly into the tubing.

Exactly why these relative proportions of tubing and louvered section will induce this down-draft and re-circulation through the tubing I am unprepared to state. It is obvious, however, that for such a down-draft to exist that pressure over the top of the tubing 20 must be greater than pressure existing in the fuel receptacle 10 below the bottom of the tubing. Apparently, the uprush of burning gases through the collar 13 induces or develops a reduced pressure below the bottom of the tubing and the inequalities in pressures at the top and bottom of the tubing consequently develop this downward flow therethrough. I find that when the tubing is present that the flame burns rather severely between the tubing 20 and the walls of the louvered section between the louver openings. The flame appears to be generally circular with indentations therein opposite the louver openings. The walls of the louvered section become quite hot and radiate heat laterally. The ascending products of combustion which ascend through the stack 17 are relatively cool and are readily observable to be free from smoke. In fact, with the opening 14

given an adjustment providing for a desired rate of burning, if the tubing 20 and its spiders are removed from the stack, the heater will immediately begin to smoke noticeably.

Experiments have been conducted to ascertain what variation from the above given preferred dimensions as it is obvious that if the tubing 20 is made relatively short and of large diameter as compared with the diameter of the collar 13 that no downward flow through the tubing will take place. On the contrary the flame within the receptacle 10 will rise inside of the tubing as well as on the outside. On the other hand if the tubing 20 is made very long and of very small diameter there will be no downward flow therethrough, or even if such flow does exist, its effect in producing smokeless and sootless heater will be negligible.

Experiments that have been conducted as to possible variations are as follows:

TEST #1

Tube Dimensions		Other Facts
Length, inches	Diameter, inches	
5.....	4.....	

Comments: Fire burns up center of tube, inclined to choke, difficult to light—very dirty—uncombusted gases are not returned

TEST #2

8 $\frac{1}{2}$	2.....	$\frac{1}{8}$ " wall. $1\frac{1}{2}$ " below bottom of stack.

Comments: No action of return at all—top of tube must be slightly above heart of fire

TEST #3

10 $\frac{1}{2}$	3 $\frac{1}{4}$	$\frac{1}{8}$ " wall. $1\frac{1}{2}$ " below bottom of stack.

Comments: Return action is present—return action not as strong as 12" length x 2" diameter

TEST #4

12.....	$1\frac{1}{4}$ (Inside) $1\frac{1}{2}$ (Outside).....	$\frac{1}{8}$ " wall. $1\frac{1}{2}$ " below bottom of stack.

Comments: Length is ideal—diameter allows slight return action $1\frac{1}{4}$ " is as small as you may go on diameter

TEST #5

12.....	2 $\frac{1}{2}$	$\frac{1}{8}$ " wall. $1\frac{1}{4}$ " below bottom of stack.

Comments: Return action is present—not as strong as with 2" diameter

TEST #6

14.....	2.....	$\frac{1}{8}$ " wall. 1 " below bottom of stack.

Comments: Return action is slight and only noticeable when regulator is wide open—no return action present under normal adjustment. Tube is too long—top of tube is above top louver

TEST #7

15.....	2 $\frac{3}{4}$	$\frac{1}{8}$ " wall. $1\frac{1}{2}$ " below bottom of stack.

Comments: No return action present—tube is too long

TEST #8

15 $\frac{1}{2}$	2 $\frac{1}{2}$	$\frac{1}{8}$ " wall. Tube flush with bottom of stack.

Comments: No return action at all—fire visible through tube. Tube must be at least $1\frac{1}{4}$ " below bottom of stack.

12.....	2.....	1½" below bottom of stack.

Comments: Return action is strongest

As a conclusion from the results of these and other tests it is apparent that the length, diameter, and position of the tubing in the louvered section is somewhat critical. In order to obtain the desired down-flow through the tubing, in a louvered section fitting on a 6" collar 13 the diameter of the tubing should be between 1¼" and 3¼". The length of the tubing should be between 10½" and 13½". The tube must project downwardly below the collar 13 a minimum of 1" and not more than 2". The top of the tubing must be below the top of the top louver openings. Some downward flow through the tubing takes place if the top of the tubing is slightly below the top of the top louver openings but the downward flow through the tubing is best when the top of the tubing 20 is approximately even with the row of louver openings next below.

It will be appreciated from the above described construction that the manufacture and installation of the tubing 20, together with its spider-forming arms is relatively simple and inexpensive. The tubing may be installed in a conventional heater very easily and at minimum expense. It is not essential that the louvered section have a 6" diameter at its bottom and an 8" diameter at its top. If the louvered section is tapered in the opposite direction and has a shape somewhat similar to that illustrated in Figs. 1 and 2 of the Leonard patent above referred to, similar results are obtainable as long as the tubing has approximately the same relative proportions with respect to the collar 13, projects downwardly into the fuel receptacle below the collar from 1" to 2" and terminates at its top below the uppermost louver opening.

Various changes may be made in the details of construction without departing from the spirit and scope of the invention as defined by the appended claims.

I claim:

1. A heater comprising a covered liquid fuel receptacle having an air inlet in the cover and a stack extending upwardly from the cover, said stack having air inlets in the walls thereof and a central tube supported therein, the top of which terminates below the uppermost air inlet openings in the walls of the stack, the bottom of the

tube extending downwardly below the cover a distance approximately equal to three-fourths of the diameter of the tube, the internal diameter of the tube being approximately one-third of the diameter of the stack at its juncture with the cover whereby down-flow of gases through the tube is induced.

2. A heater comprising a covered liquid fuel receptacle having an air inlet in the cover and a stack extending upwardly from the cover, said stack having air inlets in the walls thereof, the top of which terminates below the uppermost air inlet openings in the walls of the stack, the relative sizes of the parts being in approximately the following proportions:

Diameter of stack at juncture with the cover—6",
Diameter of stack at top of 16½" length—8",
Air openings in wall of stack disposed between 3½" and 12½" measured vertically from juncture of stack with cover,

Diameter of tube 1¼" to 3¼",
Length of tube 10½" to 13½",
Distance to which bottom of tube extends below cover—1" to 2".

3. A heater comprising a covered liquid fuel receptacle having an air inlet in the cover and a stack extending upwardly from the cover, said stack having air inlets in the walls thereof and a central tube supported therein, the top of which terminates below the uppermost air inlet openings in the walls of the stack, the relative sizes of the parts being in approximately the following proportions:

Diameter of stack at juncture with cover—6",
Air openings in wall of stack disposed between 3½" and 12½" measured vertically from cover,

Diameter of tube—2",
Length of tube—12",
Distance to which bottom of tube extends below cover—1½".
